DOOR LATCH

George E. Gilpatrick, West Hartford, Conn., assignor to The Stanley Works, New Britain, Conn., a corporation of Connecticut

Filed Apr. 15, 1957, Ser. No. 652,897

7 Claims. (Cl. 292—224)

The present invention relates to a door latch of general utility but particularly adapted for use with screen doors and storm doors. The invention relates more particularly to a door latch of this type having an improved bolt and non-lockout feature.

In door latches of the type to which the present invention relates, it is desirable to provide a spring pressed bolt which will automatically latch with the keeper when the door is moved to closed position. It also is desirable to include a locking arrangement to prevent release of the latch when it is desired to lock the door in closed position. A further desideratum is to provide a non-lockout feature to insure that the latch will be unlocked if the door is closed with the latch lock inadvertently set in locked position.

A principal object of the invention is to provide a new and better door latch having an improved bolt structure together with an improved locking arrangement of the type which is automatically released if it has been set in locking position prior to closing of the door.

It is another object of this invention to provide a new and improved door latch of the type referred to which is of simple and compact design, pleasing in appearance, inexpensive to manufacture and which is rugged and dependable for trouble-free service over a long period of time.

Other objects will be in part obvious, and in part pointed out more in detail hereinafter.

The invention accordingly consists in the features of construction, combination of elements and arrangement of parts which will be exemplified in the construction hereinafter set forth and the scope of the application of which will be indicated in the appended claims.

This invention is illustrated in the accompanying drawings, in which:

Fig. 1 is an elevational view of a door latch positioned on a door and as viewed from the inside of the door;

Fig. 2 is a top view of the door latch and door of Fig. 1;

Fig. 3 is an enlarged elevational view partially in section of the door latch shown in Fig. 1 with the cover removed;

Fig. 4 is a fragmentary cross-sectional view taken along the line 4—4 of Fig. 5;

Fig. 5 is a fragmentary bottom view of the latch mechanism with the frame in cross-section; and

Fig. 6 is a fragmentary sectional view taken substantially along line 6—6 of Fig. 2.

As shown in Fig. 1, the door latch of the present invention is mounted on a conventional pivoted door 10 which in closed position abuts against a rabbeted door jamb 11 in the usual manner. The door latch is provided with a pair of operating handle 12, 13 and a cover 14 and escutcheon plate 15 arranged on opposite sides of the door 10. Any suitable type of handle may be selected, and in the specific embodiment illustrated, handle 12 is preferably of the crank type and handle 13 is a spherically shaped knob.

2

The door latch is provided with a pivoted spring pressed bolt 16, to be described more particularly hereinafter, which cooperates with the keeper 18 suitably mounted on the door jamb 11. The finger piece 20a is provided for operating of the locking slide 20 to be described later.

Referring now to Fig. 6, the cover 14 and escutcheon plate 15 are mounted on opposite sides of the door by screws 21, with the openings 22, 23 of the cover and escutcheon plate in alignment with an aperture 24 extending through the door.

The hubs of the handles 12, 13 are rotatably positioned in the openings 22, 23 of the cover and escutcheon plate and are engaged with opposite ends of a latch operating hollow shaft or sleeve 28. Shaft 28 extends through the door opening 24 and is substantially rectangular in cross-section being preferably provided with beveled corners as shown best in Fig. 3. Handle 12 is staked to the sleeve 28 while handle 13 is removably connected to the shaft 28 by a set screw 30. Handle 13 has a center well 32 the outer end of which, in the embodiment shown, is closed by a cap 34.

Referring now to Fig. 3, the cover 14 is engaged with ears 48 on a support plate 49 positioned in abutting relationship with the door 10 and having a central bore through which the operating shaft 28 extends. The support plate is also provided with spaced bent out tabs 53 to slidably guide the movement of the locking slide 20.

As shown best in Fig. 4, the locking slide 20 is generally L-shaped in configuration and has a circular opening 56 through which the operating sleeve 28 extends when the lock is in the unlocked position. The circular opening 56 communicates with a rectangular slot 58 dimensioned to engage the operating shaft 28 and prevent it from turning when the lock is moved to the left as viewed in Fig. 4. As previously mentioned, the lock slide 20 is intended to be operated manually from the inside of the door by means of the finger piece 20a. However, the latch of the present invention is readily adapted for operation additionally, if desired, by lock means of a tumbler lock (not shown) which may be accommodated in the well 32 of handle 13 to turn the end 36 (Fig. 6) of a tubular shaft 35, disposed concentrically within shaft 28 and which can be done manually by other than lock means. For this purpose, the locking slide 20 has a vertical slot 57 for receiving the ear 45 of a lever arm 44 which extends downwardly through a slot 46 in the hollow shaft 28 and is adapted to be actuated by a rectangular rod 41 extending within the hollow shaft 28 and rotatable by the shaft 35. The arm 44 is rectangularly slotted at its upper end to embrace the rod 41 and is accommodated between the shoulders 42 of the rod 41. The opposite end of rod 41 is telescoped into extension shaft 35 having a head 36 and rotatably supported at the base of well 32 by the washer 39.

55 The latch is provided with an operating cam comprising spaced apart cam plates 60, 61 formed with a connecting web 62. The cam plates are formed, respectively, with square apertures 63, 64 for accommodating the shaft 28 and whereby the cam is mounted on shaft 28 for rotation therewith. The cam may be rotated in either direction by the handle shaft 28 but is biased to the center position shown in Fig. 3 by a torsion spring 65 having its ends extending on opposite sides of the lug 66 extending rearwardly from the bottom of cam plate 60. The ends of the spring 65 extend below lug 66 into engagement with opposite sides of the extension 67 on support plate 49 and are received in apertures 67' therein.

70 The support plate or frame 49 is provided with a bracket arm 50 for supporting a pin 68 on which the latch bolt 16 is pivotally mounted. As shown in Figs. 3, 4, the bolt 16 is substantially L-shaped and is pivotally

mounted at its corner on pin 68. The latch bolt 16 contains a downwardly depending latch leg 17 which is configured so that the latching face 17a is inclined slightly rearwardly from the longitudinal center line of the bolt and with the opposite face 17b arcuately beveled so as to provide a camming surface for retracting the bolt when it engages the keeper during closing movement of the door. The outer edge 17c also is inclined to the vertical when the bolt is in the normal latching position shown in the drawings. Integrally formed on the lower end of leg 17 is a protuberance or boss 69 adapted to engage the flange 55 on the locking slide 20 when the bolt is moved to retracted position. The protuberance or boss 69 also bears against the bracket 52 on the support plate 49 which provides a bearing surface to prevent the bolt from twisting when it engages the keeper. The other leg 19 of the latch bolt 16 extends along the top of the operating cam 60-62 and is biased into engagement therewith by means of a spring 70. The leg 19 is cut away to form a shoulder 25 providing a loading surface for the spring 70.

The operation of the latch of the present invention will be apparent from the foregoing description taken in connection with the following explanation. When the door handles 12, 13 are rotated in either direction to operate the door latch the operating cam will move the latch bolt leg 19 upwardly to pivot the latch bolt 16 to unlatching position. The tabs 60a, 61a on cam plates 60, 61, respectively, compensate for the difference in effective length of the leg 19 which is engaged by the cam when the handles are turned in opposite directions. If it is desired to lock the door latch, the locking slide 20 is moved to the left as viewed in Fig. 4 to permit the rectangular slot 58 to move into rotating preventing engagement with the operating shaft 28. Thus, neither handle may be rotated to open the door latch.

In the event that lock 20 is moved to a locking position when the door is open, an inadvertent lockout is prevented because during closing of the door, the retraction of the bolt caused by engagement of arcuate camming surface 17b against the keeper causes the projection 69 to engage the flange 55 on the locking slide 20 and move the locking slide 20 to the right to releasing position, thus leaving the door latch in an unlocked condition.

It will thus be seen that there has been provided a simple mechanism for automatically preventing inadvertent lockout utilizing a new and improved latch bolt structure in combination with a locking slide. The shape of the bolt provides an improved latching and camming action and insures trouble-free action over a long period of time. As the embodiment shown in the drawing will be subject to modification and variation by one skilled in the art, all such variations and modifications are intended to be included within the scope of the invention.

I claim:

1. In a door latch, a frame, a substantially L-shaped latch bolt pivoted at its corner on the frame and having a depending latching leg, an operating shaft extending substantially parallel to the pivot of the latch bolt and having a cam underlying the other leg of the latch bolt, means biasing the latch bolt into engagement with the cam, a cam face on one side of the latching leg to cause retraction of the bolt upon engagement of the cam face with a keeper, a locking slide mounted on the frame for movement in a direction transverse to the operating shaft and toward the latching leg of the bolt, said locking slide having means for locking the shaft when the slide is moved in said direction, and means on the latching leg for engaging the locking slide and moving it to an unlocking position when the bolt is retracted.

2. In a door latch, a latch bolt having a depending latching portion and an upper cam follower portion substantially normal thereto, said bolt being pivotally mounted for movement of the depending portion between a

latching and an unlatching position, means biasing the bolt to latching position, an operating cam associated with the follower portion for pivoting the latching portion into an unlatching position, and a locking member mounted for movement into a position preventing operation of the cam, said locking member having a portion extending into the path of retractive movement of the latching bolt when the locking member is in locking position, whereby the locking member is moved to the unlocked position by retractive movement of the bolt.

3. In a door latch, a pivotally mounted latch bolt having a depending latching leg and a cam follower extending substantially horizontally therefrom said leg being positioned to pivot between a latching and an unlatching position in respect to a keeper, means biasing the bolt to the latching position, a rotatable shaft, a cam fixed to said shaft and engaging said follower upon manual rotation of said shaft to pivot the latch bolt to unlatching position, a locking slide mounted for movement in substantially a horizontal direction and engageable with said shaft to prevent rotation thereof, and means co-operatively connecting said slide and said latching leg responsive to movement of said latching leg into an unlatching position for disengagement of said slide from said shaft.

4. In a door latch, a latch bolt having a depending latching portion and a cam follower portion in substantial right-angularity thereto, means pivotally mounting said bolt intermediate said portions, means biasing said bolt to latching position, a cam operatively associated with said follower portion for pivoting said latching portion to an unlatching position, a rotatable operating shaft, said cam being fixed to rotate with said shaft, and a locking member engageable with the shaft to prevent rotation thereof, said locking member being slidably mounted for movement between a shaft locking and a shaft unlocking position, said locking member having a depending portion positioned in the path of retractive movement of said latching portion by movement of the locking member into locking position, said depending portion being positioned for contacting engagement with said slide to move the slide out of locking engagement with said shaft by pivotal movement of said locking bolt from a locking, to an unlocking position.

5. In a door latch, a frame, a substantially L-shaped latch bolt pivoted at its corner on the frame and having a downwardly extending latching leg and an upper cam follower portion, means biasing the bolt to latching position, a rotatable operating shaft extending substantially parallel to the pivot of the latch bolt and provided with a rectangular portion, a cam mounted on said shaft with the surface thereof positioned to engage said follower portion, a shaft locking member slidably mounted on said frame for movement transversely of said shaft, said locking member having channel-forming portions engageable with the rectangular portion of the shaft to prevent rotation thereof, said latching leg and member having registerable portions separated when said member is in locking position but said locking member portion being engageable by said latching leg portion to move said locking member out of locking engagement with said shaft by pivotal movement of said latching leg from a locking to an unlocking position.

6. In a door latch, a frame mountable on a door panel and having an operating shaft rotatably mounted thereon and extending normally therethrough, a pintle fixed to said frame laterally of the panel and in parallel spaced relation to said shaft, an L-shaped latch bolt having a downwardly extending leg and pivotably mounted at its corner on said pintle for movement to and from an associated keeper mountable on a door jamb to extend normally of the axis of said pintle, a concave camming surface on said latching leg engageable by an associated keeper to move said latching leg to an unlatched position, a cam operatively associated with the other leg for pivoting said latching leg to an unlatching position, a spring

biasing said other leg into engagement with said cam and resiliently holding said latching leg in a latching position, a locking member mounted on said frame for movement in a direction transversely of said operating shaft and toward said latching leg, said locking member having means for locking said shaft when moved in said direction, and cooperating shoulders on said locking member and said latching leg engageable to move said locking member to an unlocking position when said latching leg is cammed to an unlatching position.

7. In a door latch of the type having a control shaft adapted to extend through a door panel normal to the plane of the door, a substantially L-shaped latch bolt pivoted at its corner about its axis parallel to the axis of the control shaft and having a latching leg engageable with an associated keeper, said bolt being biased to a latching position with the latching leg extending downwardly and having its outer edge inclined outwardly from the pivot, an arcuate camming face on one side of the latching leg and a slightly rearwardly inclined latching

10

15
20

face on the other side for engagement with an associated keeper positioned at a right angle to the bolt axis, an operating cam associated with the other leg of the bolt for pivoting the bolt to an unlatching position, locking means for rendering said operating cam inoperative, and means on said latching leg engageable with said locking means upon retraction of the bolt to release said locking means.
